TOBACCO STICK

Lonnie C. Mayers and Mack C. Mayers,
Lumberton, N. C.

Application January 4, 1945, Serial No. 571,328

5 Claims. (Cl. 294—5.5)

This invention relates to tobacco leaf hangers commonly known as "tobacco sticks," and an object of this invention is to provide a novel stick or tobacco leaf holder for suspending the tobacco leaves in drying barns or curing houses while the tobacco is undergoing aging and treatment.

A further object of the invention is to provide a stick of the character indicated which will effectually clamp the stem of the leaf so that the leaf will be suspended in ordinary manner during the curing processes.

It is furthermore an object of the invention to provide a stick of the character stated, in connection with which the stems of the leaves may be assembled prior to moving the clamping member into clamping operation, a condition which facilitates the placing of the tobacco on the stick, since the stick may be supported on a board of sufficient width and the leaves while resting on the board have their stems inserted between the clamping members and when the said stick has been filled, the clamping members are forced into engagement with the stems with sufficient friction to prevent displacement of the leaves while the stick is being handled as it is installed and removed from the racks of the curing houses, and by this is meant tobacco barns or other enclosures.

It is a further object of the invention to provide a stick having two clamping members, each of which is preferably of channel iron, one of said members being provided with latches or clamps which engage the other member to hold them in assembled relation with the tobacco interposed between them; and it is furthermore an object to provide an intermediate element associated with the member for exerting pressure on the tobacco at the intermediate portions of the stick.

It is a still further object of the invention to provide a tobacco stick which, as stated, will simplify the placing of the tobacco, for the reason that it can be operated by one person, whereas in the old fashioned sticks now in common use, a tying operation is followed in which two persons are required to handle the tobacco and manipulate the tying operation, so that the invention results in an inexpensive means for handling tobacco from the time it is submitted to the drying barns or the like until it is removed for pressing.

With the foregoing and other objects in view, the invention consists in the details of construction, and in the arrangement and combination

of parts to be hereinafter more fully set forth and claimed.

In describing the invention in detail, reference will be had to the accompanying drawing forming part of this application, wherein like characters denote corresponding parts in the several views, and in which:

Figure 1 illustrates a view in elevation of the edge of the stick, showing the board in section;

10 Figure 2 illustrates a plan view thereof;

Figure 3 illustrates a view of the edge of the stick, showing the tobacco stems interposed between the clamping members;

Figure 4 illustrates an enlarged detail view of 15 fragments of the stick;

Fig. 5 illustrates a longitudinal sectional view of the parts as they appear in Figure 4;

Figure 6 illustrates a sectional view on the line 6—6 of Fig. 5;

20 Figure 7 illustrates a sectional view on the line 7—7 of Fig. 9;

Figure 8 illustrates a plan view of one end of the stick;

Figure 9 illustrates a sectional view of the stick 25 on the line 9—9 of Fig. 7; and

Figure 10 illustrates a sectional view of the central clamp and parts associated with it.

In this drawing 11 denotes what may be termed 30 the base clamping member, in that it carries all of the operating mechanism of the stick and, as shown, it is of channel iron construction, with the flanges of the channel iron extending longitudinally of the stick. Near each end of the base there are inverted U-shaped abutments 12 35 which limit the space which may be occupied by the tobacco stems toward the ends of the stick. A pivot pin 13 extends transversely through the base at each end, and the end of the pin is seated in apertures in the flanges of the channel iron. A latch or clamp 14 is pivoted on the pin at each end, the said clamp having cheek pieces 14' with apertures to receive the pin, and the clamp is oscillatable on the said pin. The cheek pieces are connected by a web 15 which terminates short of the ends of the cheek pieces, as at 45 16, to form supports for the upper clamping member 17, which is likewise of channel iron, and the flanges of the two members 11 and 17 50 coact to bind the tobacco stems with such frictional contact as to prevent dislodgment of the tobacco during the handling of the stick.

It is seen from an inspection of the drawing that during the loading of the stick, the upper member 17 is supported by the end of the web 55 15 so that it is spaced from the base, and the

manipulation of the tobacco may proceed until the stick is loaded. These parts are duplicated at the two ends of the stick and when the tobacco has filled the spaces along the flanges of the base, the clamping member 17 is lowered by moving the clamps at the ends to an approximately vertical position as they are shown in Figure 2 to free the clamping member 17 so that it may descend with its flanges engaging the tobacco stems, after which the clamp is pressed downwardly over the sides of the clamping member 17; hence, the relation of parts is such that the space between the cheeks of the clamp is slightly less than the width of the clamping member 17 of the stick, so that in pressing the clamp 14 downwardly over the clamping member 17 of the stick, the frictional engagement of the cheeks with the clamping member is such as to prevent the disengagement of the clamp from the stick.

Between the ends of the stick, an inverted U-shaped bridge 18 has its sides attached to the inner surfaces of the flanges of the base and it is apertured to receive a bolt 19 held in place by a nut 20 threaded on the bolt and engaging the upper surface of the bridge and, in order to brace the bridge to prevent its collapse, a collar 21 is interposed between the under surface of the bridge and the base member 11. The bolt extends upwardly a considerable distance and the upper clamping member 17 is apertured to receive the said bolt, the said clamping member 17 being movable to an elevated position on the bolt.

A means for exerting force on the clamping member 17 between its ends consists of an apertured plate 22, the apertures of which receive the bolt 19, and the said plate is located on the upper surface of the clamping member 17. The plate has an arm 23 preferably integral therewith and when the clamping member 17 is elevated with relation to the base, it is adjusted to the position in which it is shown in Figures 4, 5, 6, etc., but when the clamping member 17 is lowered to cooperate with the base for clamping the tobacco, the plate is turned to a right angle position so that the lower end of the arm 23 engages the upper surface of the clamping member 17, and when the nut 24 threaded on the bolt 19 is operated, it exerts force on the clamping member 17 to aid in producing friction to retain the tobacco in place. Thus, the clamping member is under pressure from one end of the stick to the other, which insures a firm grip on the load.

By reason of the fact that the web terminates short of the ends of the cheek pieces, the protruding ends 25 of the cheek pieces serve as guides for retaining the upper clamping member in place while the stick is being loaded.

We claim:

1. A tobacco stick comprising two superimposed channel iron members, one of the said members having an aperture between its ends, a bolt on the other member extendable through the said aperture, a plate on said bolt engaging the outer surface of the first mentioned member, said plate having an arm movable with respect to the said member for engaging and disengaging it, a nut on the bolt for exerting pressure on the said member

and forcing it into engagement with tobacco stems on the first mentioned member, and clamps on the second mentioned member engaging the first mentioned member for holding the two members in operative clamping positions.

2. A tobacco stick comprising two channel iron members superimposed one on the other, a clamp pivotally mounted at each end of one of the members and adapted to exert pressure on the other member to hold them assembled, and means between the ends of the members for exerting pressure for forcing the two members together and clamping tobacco stems interposed between them.

3. A tobacco stick comprising two channel irons, one of which is a base member and the other movable with respect thereto for clamping the stems of tobacco leaves between them, a clamp pivotally mounted on the base member at each end and having cheek pieces adapted to straddle the other member when the two members are assembled in operative position, and a means between the ends of the stick for forcing the members together for increasing the pressure thereof on the said stem.

4. A tobacco stick comprising two channel irons, one of which is a base member and the other movable with respect thereto for clamping the stems of tobacco leaves between them, a clamp pivotally mounted on the base member at each end, said clamp comprising cheek pieces adapted to straddle the other member and having a web between them terminating short of the ends of the cheek pieces for forming supports for one of the members when separated from the other to permit the insertion of the stems of tobacco leaves between the said members, the extensions of the cheek pieces forming guides to hold the companion member during such operation, the said member being released when the clamps are moved outwardly so that the two members may coact to engage the tobacco, the said clamp being movable to embrace the other coacting member when in operative position to hold the tobacco.

5. A tobacco stick comprising two channel irons, one of which is a base member and the other movable with respect thereto for clamping the stems of tobacco leaves between them, a clamp pivotally mounted on the base member at each end, said clamp comprising cheek pieces adapted to straddle the other member and having a web between them terminating short of the ends of the cheek pieces for forming supports for one of the members when separated from the other to permit the insertion of the stems of tobacco leaves between the said members, the extensions of the cheek pieces forming guides to hold the companion member during such operation, the said member being released when the clamps are moved outwardly so that the two members may coact to engage the tobacco, the said clamp being movable to embrace the other coacting member when in operative position to hold the tobacco, and a pressing means interposed between the ends of the stick for exerting pressure on the tobacco between the ends of the stick.
